UNITED STATES PATENT OFFICE.

LINN W. MILLIS, OF KANSAS CITY, MISSOURI.

HEATING SYSTEM.

1,245,488.

Specification of Letters Patent.

Patented Nov. 6, 1917.

Application filed December 13, 1915 Serial No. 66,484.

To all whom it may concern:

Be it known that I, LINN W. MILLIS, a citizen of the United States, residing at Kansas City, in the county of Jackson and State 5 of Missouri, have invented certain new and useful Improvements in Heating Systems, of which the following is a specification.

My invention relates to improvements in heating systems.

10 It relates particularly to a system which combines hot air heating means with water or steam heating means.

One of the objects of my invention is to provide a heating system which will eliminate 15 the distribution of dust, smoke and gas from the air which is circulated by the heating means.

Another object of my invention is to provide a heating system which may be economically 20 installed and operated.

Still another object of my invention is to provide means by which the heating may be equally effected throughout the house containing the system.

25 A further object of my invention is to provide a structure which will avoid overheating of the water employed to heat the radiators or other heating units, when one or more of such units is cut off.

30 Still another object of my invention is to provide a structure which will provide a maximum of draft and rapid circulation of the air employed for heating purposes.

A further object of my invention is to 35 provide a structure which will avoid overheating of the basement or room which contains the heating mechanism.

In the accompanying drawings, which illustrate the preferred embodiment of my 40 invention,

Figure 1 is a vertical sectional view of my improved heater.

Fig. 2 is a front elevation of the same, shown connected with the radiators and 45 rooms which it is designed to heat.

Fig. 3 is a horizontal sectional view on the line 3-3 of Fig. 1.

Fig. 4 is a horizontal sectional view on the line 4-4 of Fig. 1.

50 Similar reference characters designate similar parts in the different views.

1 designates the casing of an ordinary heater or furnace provided with a fire box 2 having the usual fuel feed inlet normally 55 closed by a door 3.

4 designates the ash pit door, and 5 a

drum located above the fire box 2 and provided with an inlet or neck 6, through which the fire box discharges its gaseous products of combustion. The drum 5 is provided 60 with the usual outlet 7 discharging into the usual smoke pipe 8.

Encircling the fire box 2 is an annular water heater 9 which has connected to it, adjacent to its lower end a cold water return pipe 10.

A hot water or steam conductor 11 is connected at one end to the water heater 9 adjacent to the upper end thereof.

The conductor 11 is provided with 70 branches 12 which respectively connect with radiators 13.

The conductor 10 is provided with 75 branches 14 which respectively connect with the radiators 13.

Within the drum 5 is preferably provided a central vertical partition 15, between the upper edge of which and the drum 5 is provided a space for the passage of the gaseous 80 products of combustion.

A pivoted deflector 16, located in the inlet 6 has its lower edge secured to a horizontal rock shaft 17 which extends at its forward end to the exterior of the furnace, said forward end being provided with a 85 crank arm 18, Fig. 2, by which the rock shaft may be turned so as to dispose the deflector 16 in vertical alinement with the partition 15, as shown in solid lines in Fig. 1, or horizontally at either side of the rock 90 shaft 17, one of these last named positions being shown in dotted lines in Fig. 1.

Located in the drum 5 at the side of the partition 15 which is distant from the outlet 7, is a water heater 19, to which is connected 95 adjacent to the lower end thereof the upper end of a conductor 20, the lower end of which is connected to the conductor 10.

A conductor 21 has one end connected to the conductor 11, the other end being connected to the heater 19 adjacent to the upper end thereof.

In the operation of this portion of my invention, the hot water or steam travels from the heater 19 through the conductor 11 and 105 its branches 12 to the radiators 13. The hot water or steam passes from the heater 19 by the conductor 21 to the conductor 11. The cold water from the radiator 13 passes by the branches 14 and conductors 10 and 20 110 to the heaters 9 and 19.

When the deflector 16 is disposed, as

shown in solid lines, in Fig. 1, the gaseous products of combustion travel upwardly in the drum 5 at both sides of the partition 15, thereby heating the heater 19. The deflector 5 is so disposed, when all of the radiators 13 are in operation. If desired, in extremely cold weather, the deflector 16 may be turned horizontally to the left of the partition 15, so as to cause more of the hot gases to come 10 in contact with the heater 19.

If one of the radiators 13 is shut off, the deflector 16 may be turned to the right to the horizontal position shown in dotted lines in Fig. 1, thus cutting the heater 19 out of 15 the path of the gaseous products of combustion, and thereby reducing the area of the surface heated, thus preventing overheating of the water employed for heating purposes.

Supported by the casing 1 and located 20 wholly above the feed opening normally closed by the door 3 is a vertical cold air conductor 22 having a horizontal bottom 23 through which extends the lower end of the drum 5.

25 The upper end of the conductor 22 is provided with a cold air inlet 24, which may be covered by a grating 25.

The inlet 24 is located in a room 26 which 30 communicates with a room 27 by a door way 28, which may be closed by a door 29.

A cold air conductor 30 communicates at 35 its upper end with the room 27, and at its lower end it communicates with the cold air conductor 22 at a point a substantial distance above the lower end thereof.

Located within and encircled by the conductor 22 is an intermediate conductor 31, the upper end of which discharges into the room 26 and the lower end of which is disposed above and spaced apart from the bottom 23.

40 Located within and spaced apart from the conductor 31 is a vertical hot air conductor 32, the lower end of which is supported upon the bottom 23 by downwardly extending lugs 33, and the upper end of which discharges into the conductor 31 at a substantial distance below the upper end of the latter. Preferably the lower end of the conductor 32 is lower than the lower end of the conductor 31.

55 In the operation of the hot air heating mechanism just described, the cold air passes downwardly from the room 26 through the inlet 24 and between the walls of the conductors 22 and 31. The cold air passes then up through the hot air conductor 32 and also upwardly between the conductors 31 and 32. As the air passes upwardly through the hot air conductor 32, it is heated by the drum 5, and passing by the upper end of the space which is intermediate of the conductors 31 and 32 creates a suction in said space, thereby accelerating the upward draft in said 65 space. The cold air passing upwardly in

said space serves as an insulator to prevent the heat passing through the walls of the conductors 22 and 31. At the same time the air in said space becomes heated by radiation from the hot air conductor. 70

The heated air is discharged from the conductor 31 into the room 26. In case that it is desired to heat the room, the door 29 is opened, thereby permitting hot air to pass into the room 27 from the room 26, the 75 cold air from the room 27 passing by way of the conductor 30 into the cold air conductor 22, where it unites with the cold air entering said conductor through the inlet 24.

80 By locating the discharge end of the conductor 30 at a substantial distance above the lower end of the conductor 22, the cold air passing downwardly in the latter assists the downward draft through the conductor 30.

85 By reason of the cold air insulation between the conductors 31 and 32, the basement or other room containing the furnace does not become overheated by radiation from the drum 5 or hot air conductor 32.

90 By locating the hot and cold air conductors wholly above the feed inlet for the fuel, and in fact above all the inlets which lead toward and into the fire box, leaky joints around such inlets cannot discharge dust, smoke or gas into the air which is circulated by the air heating mechanism.

95 By combining my improved hot air and water heating mechanisms in one system, heated by a single furnace, economy of installation and of operation is effected, together with an economizing of space. It 100 will be noted that the conductors 10, 11, 20 and 21 connect the heaters 9 and 19 in parallel, instead of in series with each other. By means of this parallel arrangement of 105 the heaters, the quantity of water heated, by utilizing the deflector 16 may be varied without changing the temperature of the water heated.

110 I do not confine or limit my invention to the specific disposal and arrangement of the water heaters shown and described nor to the other details of construction, illustrated and described, as modifications, within the scope of the appended claims, may be made 115 without departing from the spirit of my invention.

What I claim is:—

1. In a heating system, a furnace having a fire box the top of which has an opening, 120 a drum contracted at its lower end forming a neck and having the latter extending into said opening at the fire box top, a smoke pipe connected to one side of said drum, a water heater in the opposite side of the drum, a water 125 jacket surrounding the fire box, a pipe connected to the water jacket and water heater, a discharge pipe leading from the water heater, a fixed vertical partition in the drum spaced at its top from the drum top, said partition 130

being arranged centrally over the fire box opening and between the water-heater and smoke pipe, and a deflector pivoted at one end in a line with the partition and below the latter and movable at its opposite end to extend across either side of the fire box opening to engage with the neck of the drum.

5 2. In a heating system, a furnace having a fire box formed with an opening in the top, a drum having a neck at its lower end communicating with said opening, a pipe connected to one side of the drum, a water heater in the opposite side of the drum, a fixed vertical partition in the drum spaced 10 at its top from the drum top, said partition being arranged centrally over the fire box opening and between the water heater and smoke pipe, and a deflector pivoted at one end in a line with the partition and below 15 the latter and movable at its opposite end to extend across either side of the fire box opening and engage the drum neck.

3. In a heating system, a furnace having a fire-box, the latter formed with an opening in its top, a drum seated on said box and having a neck at its lower end connected to said box opening, an outlet for the products of combustion in one side of the drum, a water heater in the opposite side 25 of the drum, a fixed vertical partition arranged between the outlet and said water heater and alined with the center of said fire box opening and having its lower end

arranged above said opening, and a deflector pivoted at one end and having its pivotal 35 point alined with the partition and having its opposite end movable across either side of the fire box opening and engageable with the drum neck.

4. In a heating system, a furnace having a fire box, a drum above the top of the fire box having a neck connected thereto, a cold air conductor surrounding the drum having a bottom which engages around the drum neck and further having an inlet for 40 connection to an apartment, a hot air conductor located within and spaced from the cold air conductor and having an outlet, means to connect said outlet to the apartment, said hot air conductor surrounding the 45 air drum in spaced relation thereto and being spaced above the bottom of the cold air conductor, a pipe connected to one side of the drum, a water heater in the opposite side of the drum, a fixed vertical partition 50 in the drum arranged centrally over the interior of the drum neck and between said pipe and water heater, and a deflector pivoted at one end in a line with the partition and below the latter and movable at its opposite end to extend across and engage either 55 side of the neck.

In testimony whereof I have signed my name to this specification.

LINN W. MILLIS.
